UNITED STATES PATENT OFFICE

2,534,024

PANTY

Norman Hochbaum, New York, N. Y.

Application March 31, 1948, Serial No. 18,262

1 Claim. (Cl. 2—224)

1

This invention relates to underwear and more particularly to ladies' underwear known as "panties," it being one object of the invention to provide underwear of this type which is of scant dimensions and fits snugly about a person's body and is formed along its sides with leg openings of such size that margins of the leg openings fit closely about upper portions of the legs.

Another object of the invention is to provide underwear having front and rear sections connected at their lower ends by a crotch portion and having upper ends of their opposite side edges connected in order to form leg openings and also form a waist band, the leg openings and the upper edges of the front and rear sections being bordered by strips of elastic fabric so that while the garment fits snugly about a person's legs and waist it may be stretched when put on and also in order to adjust it to provide a comfortable fit.

Another object of the invention is to provide a garment which has a front section tapered downwardly to a narrow crotch portion and a rear section which is of such shape and dimensions that it will cover the buttocks and fit snugly about the same with the lower end portion of the rear section extending forwardly and merging into the crotch portion of the garment.

Another object of the invention is to provide underwear of this character wherein the connected corners of the front and rear sections are reinforced by sheets of elastic fabric which are thicker than the elastic fabric from which the waist band and bindings for the leg openings are formed and will serve very effectively to prevent ripping of seams connecting the front and rear sections above the leg openings and also to assist in causing the garment to fit snugly about a person wearing the garment.

Another object of the invention is to provide a garment of this character which is provided with horizontally extending elastic strips spaced downwardly from upper ends of the leg openings and serving to create a closer fit while not interfering with expansion of the leg openings and the waist band.

With these and other objects in view the invention consists of an improved construction illustrated in the accompanying drawings wherein:

Fig. 1 is a front view showing the improved undergarment in use.

Fig. 2 is a side view thereof.

Fig. 3 is a rear view.

Fig. 4 is a side view showing a modified construction.

Fig. 5 is a fragmentary view looking at the in-

2

ner face of a side portion of the improved garment.

This improved garment has a body formed of thin fabric, such as rayon, silk, or the like, and of such shape that it provides front and rear sections 1 and 2 connected at their lower ends by a crotch portion 3. The front section is V-shaped and tapers downwardly from its full depth with its lower end merging into the front end of the crotch portion which is quite narrow and will fit snugly between the legs of a person wearing the garment. The rear section is of substantially the same width throughout its depth but has its lower end merging into the rear end of the crotch portion. This rear section is of such length and width that when the garment is put on it will cover the buttocks and fit snugly about the lower portion thereof, as shown in Figs. 2 and 3. End portions of side edges of the two sections are brought together and secured to each other by seams 4 which extend vertically from upper ends of leg openings 5 formed along opposite sides of the garment. The leg openings extend for substantially the full depth of the garment and the seams 4 extend from the leg openings to the upper edge of the garment, as shown in Fig. 5. Along edges of the leg openings are elastic bindings 6 which are stretchable longitudinally and secured at their ends so that they have a tendency to contract and draw the side edge portions of the garment into close fitting engagement with the legs of a person wearing the garment. These elastic bindings also cause side edges of the crotch portion to be held snugly in place but since the bindings may be stretched longitudinally, it is possible to greatly enlarge the leg openings and draw the crotch portion and the front and rear sections towards one side where it will be out of the way when responding to calls of nature. It will thus be seen that when the garment is put on with its upper portion fitting about the waist portion of a person's body and covered by a girdle, or similar foundation garment, it will not be necessary to pull the garment downwardly and then pull it upwardly and tuck it under the girdle. The garment will therefore always fit smoothly about the waist and wrinkles will not be formed which would make the garment uncomfortable. Strips or tapes 7 which are formed of elastic fabric are sewed along upper edges of the front and rear sections and form an elastic waist band extending the full circumference of the upper end of the garment. This permits the waist band portion of the garment to be stretched as it is put on and drawn upwardly into place. After the

garment has been drawn upwardly to its proper position, the elastic waist band contracts and holds the garment in snug fitting position about the waist of the person wearing the garment but allows the waist band to expand and contract when necessary.

After the seams 4 have been formed and the elastic strips 7 applied to form the waist band sheets of elastic fabric 8 are sewed into place between the leg openings and the upper edge of the garment. These reinforcing sheets 8 are formed from elastic fabric which is thicker than that used for the waist band, and therefore have greater resistance to stretching force. Upon referring to Figs. 2 and 5, it will be seen that the two reinforcing sheets are of inverted truncated triangular shape and are disposed in bridging relation to the seams 4 with portions projecting from opposite sides of the seams. The reinforcing sheets extend the full distance from upper ends of the leg openings to the upper edge of the waist band and are firmly secured by lines of stitches 9 which extend parallel to margins of the sheets. The sheets 8 serve very effectively to reinforce the garment above the leg openings and prevent the seams 4 from being ripped by stretching strains and since these sheets are stretchable transversely of the seams, and in the same direction as the waist band, they will assist in exerting contracting pull which tightens the garment about a person's waist when worn. In addition the sheets constitute wear resisting pads so disposed that when the garment is grasped at opposite sides and pulled upwardly, the thumbs will bear against the pads and thus prevent the side portions of the garment from being quickly worn and holes formed therein.

In Fig. 4 there has been shown a garment which is of a slightly modified construction. The front and rear sections, the elastic waist band and bindings for the leg openings, and the elastic pads or reinforcing sheets above the leg openings are of the same construction as previously described, the same reference numerals having been used to designate the same. The only difference between the previously described garment and that shown in Fig. 4 is that this garment is provided at each side with a strap or strip 10 formed of elastic fabric and extending across the leg opening transversely thereof and having its ends sewed to the front and rear sections in spaced relation to the upper end of the leg opening. The location of the elastic strips 10 is such that when the garment is put on and pulled upwardly into place the strips will extend across the upper portion of the thigh and elasticity of these strips will exert a pull which draws the upper portions of the front and rear sections towards each other and causes the elastic bindings for the leg openings to fit in close contacting engagement with the leg. Therefore, a snug fit will be assured about the waist as well as about a person's legs and side edges of the crotch portion will also be held snugly in place.

From the foregoing description of the con-

struction of my improved device, the operation thereof and the method of assembly will be readily understood, and it will be seen that I have provided a comparatively simple, inexpensive and efficient means for carrying out the various objects of the invention.

While I have particularly described the elements best adapted to perform the functions set forth, it is apparent that various changes in form, proportion and in the minor details of construction may be resorted to, without departing from the spirit or sacrificing any of the principles of the invention.

Having thus described the invention, what is claimed is:

15 An undergarment comprising front and rear sections gradually reduced in width towards their lower ends and joined at their lower ends by a narrow crotch portion, said sections having upwardly converging side edges merging at their lower ends into opposite side edges of the crotch portion and forming upwardly tapered leg openings extending from the crotch portion to a point spaced downwardly from the upper edge of opposite sides of the garment, the companion side edges of the front and rear sections intersecting at the said point, upper portions of the said side edges of the front and rear sections extending vertically above the leg openings and being sewed together in meeting relation to each other and forming straight seams extending vertically between upper ends of the leg openings and the upper edge of the garment, elastic bindings for edges of the leg openings, a strip of elastic fabric extending along the outer face of upper edge portions of the front and rear sections circumferentially of the garment and forming an elastic waist band for the garment stretchable circumferentially thereof, and reinforcements for side portions of the garment between the upper edge of the waist band and upper ends of the leg openings, said reinforcements being each of inverted and truncated triangular shape and sewed against outer faces of the front and rear sections with portions of the reinforcements extending forwardly and rearwardly from opposite sides of the seams connecting the front and rear sections above the leg openings, said reinforcements being formed of elastic fabric thicker than the elastic waist band and stretchable circumferentially of the garment.
